CLAIM

The ornamental design for a cheese slicer, as shown and described.

DESCRIPTION

FIG. 1 is an isometric of a cheese slicer showing our new design;

FIG. 2 is a top plan view thereof;

FIG. 3 is a bottom plan view thereof;

FIG. 4 is a right side elevational view thereof. The opposite left side is the same as the right side elevational view;

FIG. 5 is a front elevational view thereof; and,

FIG. 6 is a rear view thereof.
